CLAIM

The ornamental design for a storage container as shown and described.

DESCRIPTION

FIG. 1 is a perspective view of my design of a storage container;

FIG. 2 is a front, top perspective view of the storage container of FIG. 1;

FIG. 3 is a right, top perspective view of the storage container of FIG. 1;

FIG. 4 is a left, top perspective view of the storage container of FIG. 1;

FIG. 5 is a back, top perspective view of the storage container of FIG. 1; and,

FIG. 6 is a top view of the storage container of FIG. 1. The colors or contrast of color of different components of the claimed storage container are examples of possible colors or contrast thereof and are not part of the claimed design.

1 Claim, 6 Drawing Sheets
